UNITED STATES PATENT OFFICE.

FRED J. BAIRD, OF CLEVELAND, OHIO.

COMMUTATOR-BAR.

1,168,261.

Specification of Letters Patent. Patented Jan. 11, 1916.

Application filed October 17, 1914. Serial No. 867,108.

To all whom it may concern:

Be it known that I, FRED J. BAIRD, a citizen of the United States, resident of Cleveland, county of Cuyahoga, and State of Ohio, have invented a new and useful Improvement in Commutator-Bars, of which the following is a specification, the principle of the invention being herein explained and the best mode in which I have contemplated applying that principle, so as to distinguish it from other inventions.

My invention relates to commutator-bars, its object being to provide a commutator-bar which will be economical of manufacture, which will contribute to the economy of construction of the commutator, and which will be efficient in the performance of its function.

Said invention consists of means herein-after fully described and particularly set forth in the claims.

The annexed drawings and the following description set forth in detail certain means embodying my invention, the disclosed means, however, constituting but one of various mechanical forms in which the principle of the invention may be applied.

In said annexed drawings:—Figure 1 represents an end elevation of a commutator of the closed type and embodying my invention. Fig. 2 represents an axial section of such commutator. Fig. 3 represents an end elevation of a commutator-bar of the heretofore and commonly used type, and Fig. 4 represents a side elevation thereof. Fig. 5 represents an end elevation of a blank bar from which the commutator-bar elements constructed in accordance with my invention, are cut, and Fig. 6 represents a side elevation of a fragmentary portion thereof. Fig. 7 represents an end elevation of a commutator-bar element constructed in accordance with my invention and Fig. 8 a side elevation thereof.

The illustrated embodiment of my invention comprises a commutator-bar formed of two elements 1 and 1^a. Each element consists of a main or body portion 2 having the dove-tail bottom 3. Projecting radially with reference to the commutator's axis, from one end of the main or body portion 2 is the radial portion 4. This main or body portion has a lateral face 5 which when the commutator is assembled lies in a plane which contains the commutator's axis, as shown in Fig. 1. The opposite face

6 lies in a plane which also, when the commutator is assembled, contains said axis. The one lateral face 7 of the radial portion 4 lies in the same plane with the lateral face 5 of the body portion, as shown in Fig. 7 and the opposite lateral face 8 of said radial portion lies in a plane different from that containing the corresponding lateral face 6, as also shown in said Fig. 7. This face 8, however, is parallel with the face 6 and lies between the plane of face 6 and the plane of faces 5 and 7, as shown.

Each commutator-bar consists of two elements such as have just been described, one element, however, being a left and the other a right, that is, they are symmetrical in cross-section but have their corresponding faces reversed. When these elements are assembled in the commutator, a left and a right are placed in juxtaposition with the faces 6 in contact, as shown in full and dotted lines in Fig. 7, and when so placed form an outer radial groove or slot 9 parallel with the commutator's axis having parallel side faces. These pairs of elements so placed are assembled to form the complete commutator as shown in Figs. 1 and 2, in which the dove-tail inner portion of each commutator-bar is held by the rings 10 and 11 joined together by the bolts 12, passing through one of the rings and threaded into the other, as shown. As is customary, suitable insulating rings of mica, 13 and 14, are interposed between the commutator-bars and the rings 10 and 11 and suitable insulating strips 15 placed between adjoining commutator-bars, so that the general construction of the commutator is identical with that heretofore employed. It will thus be seen that the elements so assembled provide the required radial slots 9 which receive the leads from the armature coils and in which such leads are secured in the usual manner. In this way a commutator is constructed in an efficient and economical manner.

In forming the commutator-bar elements just described, I first take a suitable bar of copper and by means of suitable dies draw same into what is known as mill lengths having the form shown in Figs. 5 and 6 in which the cross-section is identical in contour with the end elevation of the completed bar, as an inspection of Figs. 5 and 7 will indicate. In drawing this blank bar, however, I resort to the drawing process in which the bar passes through a suitable

number of dies which give it the required cross-section and in what at least the last two passes are made while the copper is comparatively cold. This results in what is known as cold or hard-drawn copper. Copper drawn in this manner is of higher conductivity and more uniform in molecular structure than rolled, forged or cast copper. The dies employed are such as to give the cross-section which is illustrated, such cross-section being uniform throughout, both as to area and contour. Such section is bounded by a straight line *a* on one side, two lines *b* and *c* on the other side, connected at their inner ends by a third line *d*, the outer ends of said two lines *b* and *c* and the top and bottom of line *a* being joined by lines *e* and *f* respectively, as shown in Fig. 5. Line *b*, as shown, lies intermediately of the line *a* and an upward extension of line *c*. This blank bar is then formed by means of suitable punching dies into the form shown in Figs. 7 and 8, thus forming the complete bar element.

Heretofore it has been customary to first form a mill-length blank bar having the cross-section whose contour is that illustrated by Fig. 3 in which the top and bottom dimensions were those of the complete commutator-bar. From this blank mill-length was then punched the form shown in Fig. 4 after which the commutator-bars were assembled in the usual manner to form the complete commutator. After this assembling was completed, the commutator was then placed in a milling or slotting machine and the slots 9 milled or cut. By constructing the commutator-bar according to my invention, however, it will be noted that this milling or cutting operation is entirely eliminated as well as all the procedure incident thereto, all of which results in a very material economy of operation and in a considerable saving of metal, as will be readily understood by those skilled in the art.

Having fully described my invention, what I claim and desire to secure by Letters Patent is:

- As a new article of manufacture, a hard-drawn continuous copper bar, having a cross section bounded wholly on one side and partly on the opposite side by converging lines, the boundary on the side last-mentioned being completed by the side and bottom contour of part of a straight sided slot, the upper and lower boundaries of the cross section being straight lines.
- As a new article of manufacture, a straight bar of hard drawn copper forming a blank from which commutator bar elements may be cut and having a cross-section uniform throughout, both as to area and

contour; said section being bounded entirely upon one side by a straight line and upon the other side by two lines and a third line connecting their inner ends, and a top and bottom line connecting the outer ends of said two lines with the said first-named line.

3. As a new article of manufacture, a commutator bar element consisting of a main or body portion having a radial portion integral therewith; said radial portion and the body portion adjacent thereto being bounded by a plane surface on one side, two plane surfaces on the other side connected at their inner ends by a third plane surface; and a top and bottom surface connecting the outer extremities of said two plane surfaces and said first-named plane surface.

4. As a new article of manufacture, a commutator bar element consisting of a main or body portion having a radial projecting portion integral therewith, said main or body portion having two lateral longitudinal faces angularly related to each other, each of which faces constitutes one entire face of said main or body portion, and said radial projecting portion having one of its lateral longitudinal faces occupying a plane different from either of the planes occupied by the lateral longitudinal faces of the body portion and forming one side of a straight sided slot.

5. A commutator-bar comprising two elements, each element comprising a main or body portion and a radial portion; said main or body portions being in contact with each other and said radial portions forming a longitudinal groove or slot.

6. A commutator-bar comprising two elements, each element consisting of a solid bar of copper comprising a main or body portion and a radial portion; said main or body portions being in contact with each other and said radial portions forming a longitudinal groove or slot.

7. As a new article of manufacture, a commutator-bar element composed of solid copper and comprising a main or body portion and a radial portion; a cross-section taken upon a plane passing through the radial portion and perpendicular to the axis of the element being entirely bounded by a straight line on one side, two lines on the other side connected at their inner ends by a third line; and a top and bottom line connecting the outer ends of said two lines and said first-named line.

Signed by me, this 1st day of October, 1914.

FRED J. BAIRD.
